CLAIM

The ornamental design for an RFoG telecommunications node, as shown and described.

DESCRIPTION

FIG. 1 is a top perspective view of an RFoG telecommunications node showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line shown in the drawing views is for the purpose of illustrating unclaimed environment only and forms no part of the claimed design.
